UNITED STATES PATENT OFFICE.

FRANKLIN G. HOBART, OF BELOIT, WISCONSIN, ASSIGNOR TO FAIRBANKS,
MORSE & COMPANY, OF CHICAGO, ILLINOIS, A CORPORATION OF ILLINOIS.

SPRAYER.

No. 854,852.

Specification of Letters Patent.

Patented May 21, 1907.

Application filed May 1, 1906. Serial No. 314,728.

To all whom it may concern:

Be it known that I, FRANKLIN G. HOBART, a citizen of the United States of America, residing at Beloit, in the county of Rock and State of Wisconsin, have invented certain new and useful Improvements in Sprayers, of which the following is a specification, reference being had therein to the accompanying drawings.

10 My invention relates to new and useful improvements in sprayers, or spray nozzles, and is particularly adapted for use in scrubbers for suction gas producers.

15 The object of the invention is to produce a sprayer which may be adjusted to give an evenly scattered spray while varying the volume of water.

20 The novel construction and arrangement of parts by which I have accomplished this object will be more fully hereinafter described and set forth in the claims.

In the drawings, Figure 1 is a vertical central section through the sprayer, and Fig. 2 is a perspective view of the adjustable closure.

25 A is a preferably tubular body member having one end open and at the other an annular rim or flange *a* seating around the edge of the opening B' in the top of the scrubber B and A' is a preferably conical nozzle projecting into the opening B' and having an axial outlet opening *a'*. The interior of the body member forms a cylindrical chamber having a downwardly and inwardly tapering lower end terminating in the outlet *a'*. The inlet C to the casing is tangential and is arranged with a suitable gland C' for connection with the water supply.

30 D is a combined closure for the open end of the body and valve for the inlet and consists in a circular top D' and an annular projection E fitting the chamber in the body member. The lower edge of this projection forms a spiral *d* and the ends of the spiral are connected by a vertical portion *e*.

45 When a full volume of water is desired, the closure D is rotated to bring the portion *e* beside the inlet C, and when a lesser volume is desired the closure is rotated to bring the portion *e* partially across the inlet. Thus 50 the volume of water is restricted without restricting the pressure.

To facilitate the adjustment of the valve,

the top D' is provided with suitable means, such as the spaced segmental lugs *d'* which may be engaged by a bar or any suitable tool. 55

Any desired means may be employed for securing the sprayer to the scrubber, but I prefer to employ the means shown in the drawings. This consists of a cross bar or yoke G engaging the tops of lugs *d'* and holding the top on the sprayer with the valve set in any desired position of adjustment, and, at the same time, holding the whole sprayer firmly to its seat on the scrubber. The yoke G is drawn down and held by means of nuts 60 H' on the studs H passing through apertures in the yoke, the lower ends of said studs being secured to the scrubber top.

What I claim as my invention is:

1. In a sprayer, the combination of a body 70 member having a chamber substantially circular in cross-section, and provided with a tangential inlet and an outlet, and a rotatively adjustable controlling member for the inlet, held within the chambered body against 75 relative longitudinal movement.

2. In a sprayer, the combination with a body member formed with a chamber having a portion substantially circular in cross-section, and provided with a tangential inlet 80 and outlet, of a rotatively adjustable cut-off member within the chamber controlling the inlet, and means for operating the cut-off.

3. In a sprayer, the combination with a body member forming a cylindrical chamber 85 having a tangential inlet and an axial outlet, of a member in said chamber having a spiral surface between said inlet and outlet and means for adjusting said member to variably restrict said inlet for the purpose described. 90

4. In a sprayer, the combination with a body member having formed therein a substantially circular chamber, and provided with a tangential inlet and an axial outlet, of a cut-off valve for the inlet mounted within 95 the chambered body for rotary adjustment, and held against relative axial movement, and means for adjusting said valve.

5. In a sprayer, the combination of a body member formed with a substantially circular chamber, open at one end, and provided with a tangential inlet and an axial outlet, and a combined closure and valve member mounted 100 within the body for rotary adjustment, and

held against relative axial movement, said member acting to close the chamber and variably restrict the inlet.

6. In a sprayer, the combination of a body member formed with a substantially circular chamber, open at one end and provided with a tangential inlet and an axial outlet, and a rotatable closure for said open end carrying an annular flange, projecting into said chamber, formed with a spiral surface, substantially as and for the purpose described.

7. In a sprayer, the combination of a body member having a circular chamber therein, and provided with a tangential inlet and an axial outlet, and a cut-off member for variably restricting the inlet arranged within the chamber for adjustment in a horizontal plane.

8. In a sprayer for gas producer scrubbers, the combination with an apertured scrubber top, of a cylindrical casing seated in said aperture having an axial outlet registering with

said aperture, and having a tangential inlet, a closure for the top of said casing, studs on the scrubber top on opposite sides of said aperture, a yoke engaging said closure and apertured to engage said studs, and adjustable means for holding said yoke against said closure.

9. In a sprayer, the combination with a body member provided with a cylindrical chamber, having one end substantially conical with an axial outlet therein, said chamber having a tangential inlet, of a rotatable closure for the other end of said chamber held from longitudinal movement, and means carried by the closure and operating upon its rotation to variably restrict the inlet.

In testimony whereof I affix my signature in presence of two witnesses.

FRANKLIN G. HOBART.

Witnesses:

AMELIA WILLIAMS,
NELLIE KINSELLA.
